DESIGN FOR A DRESS OR SIMILAR ARTICLE

Mortimer M. Breskin, New York, N. Y.

Application January 25, 1943, Serial No. 109,336

Term of patent 3½ years

To all whom it may concern:

Be it known that I, Mortimer M. Breskin, a citizen of the United States of America, residing in New York city, county of New York, and State of New York, have invented a new, original, and ornamental Design for a Dress or Similar Article, of which the following is a specification, reference being had to the accompanying drawing, forming part thereof, wherein,

I claim:

The ornamental design for a dress or similar article, substantially as shown.

MORTIMER M. BRESKIN.
